UNITED STATES PATENT OFFICE

154,511

DESIGN FOR A PLATE OR SIMILAR ARTICLE

Allan Rosenfeld, New York, N. Y.

Application January 22, 1948, Serial No. 143,974

Term of patent 3½ years

(Cl. D44—15)

To all whom it may concern:

Be it known that I, Allan Rosenfeld, a citizen of the United States of America, residing in New York, county of New York, and State of New York, have invented a new, original, and ornamental Design for a Plate or Similar Article, of which the following is a specification, reference being had to the accompanying drawing, forming part thereof.

Fig. 1 is a top plan view of a plate or similar article showing my new design.

Fig. 2 is an edge view thereof.

I claim:

The ornamental design for a plate or similar article, substantially as shown.

ALLAN ROSENFELD.
